UNITED STATES PATENT OFFICE.

EMMA BOWERMAN, OF NEW YORK, N. Y.

RECEPTACLE.

Application filed March 21, 1921. Serial No. 453,944.

To all whom it may concern:

Be it known that I, EMMA BOWERMAN, a citizen of the United States, residing at New York city, in the county of New York and State of New York, have invented a certain new and useful Improvement in a Receptacle, of which the following is a specification.

The object of my invention has been to provide a receptacle which may be made flat for shipment and may be readily erected by the purchaser into form for use, and particularly one which may be used as an individual ash-tray to be destroyed after use, and to such ends my invention consists in the receptacle hereinafter specified.

In the accompanying drawings:

Fig. 1 is a vertical sectional view of a receptacle embodying my invention.

Fig. 2 is a plan view thereof.

Figs. 3 and 4 are similar views of the receptacle of Fig. 1 in flattened condition for shipment.

My invention is capable of embodiment in many different forms, and while I have chosen for illustration an embodiment which is the best embodiment thereof known to me, such embodiment is to be regarded as typical only of the many possible embodiments and my invention is not to be confined thereto.

The particular embodiment of my invention shown in the drawings is a receptacle for cigar and cigarette ashes, which is intended for use in hotels, and is so inexpensive that the hotel can afford to furnish a new one for each guest, so that each guest shall have a clean one, and one which will serve as an advertisement of the hotel if the guest takes it away with him, and yet the hotel will be protected from the considerable expense due to guests taking away the usual expensive metal or china ash trays, as now frequently occurs.

The said ash tray, when in form for shipment, consists of a disk A of paper having a facing A' of asbestos or other non-inflammable material. The said disk A is fastened to another and preferably smaller disk B, which may be of stiff cardboard, the disk A being thin enough to be easily bendable for reasons which will soon appear.

The disk A has a series of metal strips C fastened thereto in radial position and extending across the asbestos face thereof and fastened to the edge, as by being bent over

the edge and back along the under face of said disk. Fastenings D secure the strips C and the disks A and B together.

Means for forming a cigar holder are also preferably provided in the form of a metal strip E which may be secured at one end by one of the fastenings D and which carries at the other end a metal plate F that is preferably scored parallel to the strip, so that it can readily be bent up into a rounded shape to hold a cigar.

When the blank shown in Figs. 3 and 4 is to be erected into condition for use, the user simply bends the outer ends of the metal strips C into substantially vertical position relative to the base B, the point of bending not only being automatically determined by the outer fastenings D, but being indicated to the user by the position of such fastenings and preferably also by a circle on the disk A passing through said outer fastenings D. Thus the outer portion of the disk A is formed into and held in fluted shape, making a receptacle or dish that is efficient and also attractive in appearance.

The strip E is then bent upward and outward and is hooked over the edge of the receptacle, which brings the plate F into horizontal position. Finally, the said plate F, owing to its being scored, is readily curved by means of the fingers into shape to hold a cigar.

If desired, the portions of the strips C which lie upon the bottom of the receptacle thus formed may be covered with a disk of asbestos or other non-inflammable material.

It will be seen that I have provided an ash tray which is so compact in its blank form that a large number of them can be shipped in a small space. It will also be seen that the blanks are very readily formed into receptacle shape without requiring skill in doing so and that the receptacle is both safe from fire and very convenient to use. The ash receivers are so cheap that, as stated, hotels can readily afford to give one to each guest, and if imprinted with the name of the hotel they will form a very attractive advertisement, as the guest is likely to want to take one away with him, not only as a souvenir and because of its convenience, but also because of the interest its construction would have.

I claim:

1. An ash tray comprising fibrous sheet material having its edges bent up in fluted

form to constitute the sides of such tray, and stiffening applied to said edges for retaining them in said form.

2. An ash tray comprising sheet material, 5 having its edges bent up in fluted form to constitute the sides of said tray, and bendable-metal retaining means attached to said edges for retaining them in said form.

3. A receptacle comprising a single sheet 10 of paper or like material, the sides being formed by bending up the material around the periphery and being held in erect position by strips of metal secured to the bottom and to the sides of said receptacle.

15 4. A receptacle comprising a single sheet of paper or like material, the sides being formed by bending up the material around the periphery and being held in erect position by strips of metal secured to the bottom 20 and to the sides of said receptacle, the said sides being fluted.

5. A receptacle formed of paper comprising a disk of paper or similar material, the central portion of said disk forming the bottom of the receptacle, the outer portions of 25 said disk being bent up to form the sides and metal strips being secured to the bottom and to the sides to hold said sides in erected position.

30 6. A receptacle comprising a relatively stiff base, a disk of paper or similar material secured to said base, said disk having a series of metal strips radially secured thereto, the means for securing said strips to said base being placed within the confines of the 35 bottom of the receptacle, said strips extending substantially to the periphery of the disk and being secured thereto, the material between said strips being fluted.

40 7. A receptacle comprising a relatively stiff base, a disk of paper or similar material secured to said base, said disk having a series of metal strips radially secured thereto, the means for securing said strips to said base being placed within the confines of the 45 bottom of the receptacle, said strips extending substantially to the periphery of the disk and being secured thereto, the material between said strips being fluted, and a cigar 50 holder consisting of a metal strip secured to said base and to a side of the receptacle, and means on said strip for holding a cigar.

8. A receptacle comprising a relatively stiff base, a disk of paper or similar material 55 secured to said base, said disk having a series of metal strips radially secured thereto, the means for securing said strips being placed within the confines of the bottom of the receptacle, said strips extending substantially 60 to the periphery of the disk and being secured thereto, the material between said strips being bent so as to accommodate without cutting, the excess of periphery caused in forming the said disk into the receptacle.

9. A blank for a receptacle comprising a flat disk of paper or similar material, the central portion of which is adapted to form the bottom of the receptacle, there being metal strips secured to said bottom and to 70 the peripheral portions of the blank, whereby the sides of the receptacle may be formed by bending up said peripheral portions and said metal strips.

10. A blank for a receptacle comprising a 75 substantially flat sheet of fibrous sheet material and bendable metal-retaining means secured to the edge of said sheet, whereby said edge may be bent up into fluted form to constitute the sides of said receptacle and 80 may be held in such form by said metal retaining means.

11. The combination of a base for a receptacle, said base being formed of relatively stiff material and a blank for said receptacle comprising a disk of paper or like material, the central portion of which disk is adapted to form the bottom of the receptacle, said central portion being fastened to said base and radial metal strips secured to 90 said base and to the peripheral portions of the disk, whereby the sides of the receptacle may be formed by bending up said metal strips.

12. The combination of a base for a receptacle, said base being formed of relatively stiff material and a blank for said receptacle comprising a disk of paper or like material, the central portion of which disk is adapted to form the bottom of the receptacle, said 100 central portion being fastened to said base, and radial metal strips secured to said bottom and to the peripheral portions of the disk, whereby the sides of the receptacle may be formed by bending up said metal strips 105 and fluting the material between said strips.

13. A blank for a receptacle comprising a flat disk of paper or similar material, the central portion of which is adapted to form the bottom of the receptacle, there being 110 metal strips secured to said bottom and to the peripheral portions of the blank, whereby the sides of the receptacle may be formed by bending up said peripheral portions and said metal strips, said blank having attached 115 thereto a metal strip carrying a metal plate, said strip being adapted to be bent up and over the edge of the receptacle and said plate being adapted to be bent into a trough shape to hold a cigar.

14. The combination of an ash tray formed of asbestos and a support therefor of paper made of a vegetable material substantially fitting and sustaining said tray throughout its under surface.

In testimony that I claim the foregoing, I have hereunto set my hand this 9th day of March, 1921.

EMMA BOWERMAN.
